UNITED STATES PATENT OFFICE.

CHARLES A. RICH, OF NEW YORK, N. Y., ASSIGNOR TO ANSCO COMPANY, OF BINGHAMTON, NEW YORK, A CORPORATION OF NEW YORK.

FINDER FOR PHOTOGRAPHIC CAMERAS.

1,280,844.

Specification of Letters Patent.

Patented Oct. 8, 1918.

Application filed January 16, 1918. Serial No. 212,035.

To all whom it may concern:

Be it known that I, CHARLES A. RICH, a citizen of the United States, and a resident of the borough of Manhattan, city, county, and State of New York, have invented a new and useful Improvement in Finders for Photographic Cameras, of which the following is a specification, reference being had to the accompanying drawings.

10 It is the purpose of this invention to construct a finder which shall be relatively inexpensive, unusually compact in construction, not liable to derangement, and which may be quickly and easily adjusted for vertical or horizontal exposures.

Figure 1 is a front view of a finder embodying the invention, the hood being elevated; Fig. 2 is a side elevation of that which is shown in Fig. 1; Fig. 3 is a vertical sectional view of that which is shown in Fig. 2, the finder being presented in the opposite direction; Fig. 4 is a plan view of the finder; Fig. 5 is a transverse vertical sectional view taken on the line 5—5 of Fig.

25 3 and looking in the direction of the arrows; Fig. 6 is a front elevation, showing the parts in the position they occupy during their tilting movement from the vertical to the horizontal position; Fig. 7 is a vertical 80 sectional view showing the position of the parts when the transition from the vertical to the horizontal position has been accomplished; Fig. 8 is a detail showing the construction of the fixed member of the finder.

30 In the drawings 1 represents the movable lens and mirror supporting part of the finder, 2 is the outer fixed casing, which is preferably supported upon a bracket 3, see Fig. 1, and immovably fastened to an appropriate part of the camera, as by a horizontal flange 4, and screws or rivets 5. 6 is the lens in the usual lens casing 7. 8 is the mirror, 9, the finder lens, 10 the usual hood. 11, see best Figs. 5, 7, and 8, are the two 45 view openings, one for vertical and the other for horizontal exposures, which are or may be made as usual. The movable or oscillating lens and mirror carrying inner frame is pivotally supported within the fixed outer 50 casing at one side by the main lens casing 7, as shown best in Fig. 3, and at the other side by a pivot or trunnion 12. A yoke like frame 13, having two curved arms 14, 14, one at each end, the ends of which respectively engage with the casing for the main

lens and with the pivot or trunnion 12, is provided in its central part and about midway between the two arms, 14, 14, with a rearwardly extending pin or post 15, upon which is arranged a spring 16, which bears against a pin or washer 17 at one end and against the inner surface of a portion of the fixed frame 2 at the other end, and the cross member of the yoke 13 is provided with two or more inwardly extending pins 18, which enter holes in the fixed frame as shown, whereby the yoke is supported. These pins may beneficially be bent over at their inner ends (see Fig. 5) so as to make them hook like in form as shown.

It will be noted that the arm 14 which engages with the pivot or trunnion 12 makes that engagement by means of a mere opening or hole made in the end of the arm which properly engages with the pivot, but, 75 as best seen in Figs. 1, 2 and 6, the companion arm on the opposite side has a bifurcated extremity adapted to enter into an annular groove 19, see Figs. 2 and 3, on the exterior surface of the casing for the main lens, so that this casing may itself act as the journal or trunnion for that side of the lens and mirror bearing movable frame. 20 (see Fig. 5) is a slot made in the appropriate side of the fixed frame 2, through 85 which the pivot 12 moves during the tilting movement of the lens bearing frame.

The operation is as follows: In order to effect the transit of the lens bearing frame from say the vertical to the horizontal position, or vice versa, the hood 10 may be taken hold of by the operator and pressed in the appropriate direction, whereupon as the lens and mirror bearing frame tilts under the pressure thus exerted, its upper corners (see 90 Fig. 6) bear against the upper plate of the fixed frame 2, and inasmuch as the radius from the axis of the lens to either corner of the movable frame is greater than from the axis of the lens to the middle of either side, there is of course downward pressure exerted upon the arms 14 of the spring controlled yoke 13, so that it is made to tilt upon the hooks or pins 18 at the upper edge of its crossbar, the lower edge of the crossbar being tilted outwardly from the fixed frame and the spring 16 correspondingly put under stress, and as soon as the upper corner of the lens bearing frame has passed the dead point, so to speak, then the pressure exerted 100 105 110

by the spring 16, which causes it to maintain contact with the under side of the horizontal plate of the fixed frame 2, will aid in effecting the transit and will assure its 5 attaining and maintaining its new position, because the spring 16 will continuously exert pressure through the yoke and its arms 14 upon the oscillating mirror and lens carrying frame, causing it to properly maintain 10 either of the two positions in which it may be moved. The spring also affords desirable cushioning or yielding action during the stated movements, so that there is no objectionable binding of one part upon the other. 15 It will be obvious to those who are familiar with such matters that modifications may be made in the details of construction without departing from the essentials of the invention. I therefore do not limit myself 20 to such details.

I claim:

1. A finder for cameras embodying a fixed outer frame provided with requisite view openings, a movable lens and mirror bearing frame within the fixed frame, and a spring actuated yoke supported by the fixed frame and which pivotally supports and controls the movements of the inner movable frame. 25
2. A finder for cameras embodying a fixed outer frame provided with requisite view openings, a movable lens and mirror bearing frame within the fixed frame, a yoke sup- 30

ported upon the fixed frame and which pivotally supports the inner movable frame, said yoke being provided with a spring 35 whereby it is held in position and pressure exerted on the movable frame through the pivotal connections between the yoke and it during the movements of the movable frame. 40

3. In a finder a fixed outer frame provided with requisite view openings, a movable inner lens and mirror bearing frame, a yoke exterior to both frames which pivotally supports the inner frame, and a spring which engages with the yoke and normally 45 tends to hold it in position and to assist the transit of the inner frame during its changes of position and insure its attaining the desired positions at each end of its movement. 50

4. In a photographic finder a fixed outer frame provided with requisite view openings, a movable lens and mirror carrying inner frame, a yoke comprising a cross-bar having a laterally extending arm at each end which pivotally support the inner frame 55 means on the cross-bar whereby the yoke is supported upon the fixed frame and a spring which exerts its tension on the yoke and tends to hold it to the fixed frame and to aid in the movements of the inner frame. 60

In testimony whereof I have signed my name to this specification.

CHARLES A. RICH.
